UNITED STATES PATENT OFFICE.

HIESTER SEIDERS, OF READING, PENNSYLVANIA.

MULTICOLOR-INKING MECHANISM.

Original application filed November 2, 1923, Serial No. 672,339. Divided and this application filed April 2, 1925, Serial No. 20,083.

To all whom it may concern:

Be it known that I, HIESTER SEIDERS, a citizen of the United States, residing at Reading, in the county of Berks and State 5 of Pennsylvania, have invented certain new and useful Improvements in Multicolor-Inking Mechanisms, of which the following is a specification.

This invention relates to a multi-color 10 inking mechanism and is a division of my application for multi-color wrapping paper printing machines filed November 2, 1923, Serial Number 672,339.

In the accompanying drawings, which are 15 for illustrative purposes only and are therefore not drawn to scale:

Figure 1 is a fragmentary longitudinal sectional view of a wrapping paper printing machine, illustrating the application of my 20 multi-color inking mechanism.

Figure 2 is a transverse sectional view through the printing cylinder and multi-color inking mechanism.

Figure 3 is a side elevation of the printing cylinder and multi-color inking mechanism, and Figure 4 is a plan view of the printing cylinder.

The casing of the machine comprises the base 1, top 2 and side panels 3.

30 A printing cylinder 40 is journaled in the casing and is provided at its ends with gear wheels 41. A sheet of rubber 42 is laced upon the cylinder and the printing characters stand up from the surface of the sheet.

35 As the cylinder turns the roller 30 holds the paper 12 against the printing characters of the sheet.

The inking mechanism comprises a fountain 45 which is supported at its ends upon 40 lugs 46 mounted at the inner surfaces of the side panels. Partition walls 47 divide the fountain tray compartments adapted to retain ink of different colors. Rollers 48 are journaled transversely of the compartments and ribbons 49 are trained around the rollers 48. A ratchet wheel 50 is mounted upon the shaft of one of the rollers 48 and lever 51 is pivoted upon said shaft. A pawl 52 is pivoted upon the lever and is 50 adapted to engage the teeth of the ratchet wheel. A link 53 is pivoted to the free end of the lever and is mounted upon an eccentric 54 attached to the shaft of the cylinder. Therefore, as the cylinder turns the link is 55 moved longitudinally and the lever is swung

whereby the lever is rocked and the pawl engaging the teeth of the ratchet wheel turns the wheel by stages and as the attached roller is turned the ribbons are moved in orbits in the ink fountain and take 60 up the different colored ink. An ink distributing roller 55 is journaled upon the fountain tray and is provided at its ends with gear wheels 56 which mesh with the gear wheels upon the printing cylinder. 65 The roller 55 bears upon the upper runs of the ribbons and takes the ink up from the same and applies the different colored ink to the faces of the printing characters upon the printing sheet. As the paper comes in 70 contact with the faces of the characters the ink is applied to the paper.

From the foregoing description taken in connection with the drawings, it is thought that the construction, operation and advantages of my invention will be readily understood without requiring a more extended explanation.

Having described the invention, what is claimed is:—

1. In a machine of the character described, a casing, a printing cylinder journaled therein and provided at its ends with gear wheels, an ink fountain located below the cylinder, rollers journaled in the fountain, ribbons trained around said rollers, means for moving the ribbons by stages and operated from the cylinder and an ink distributing roller resting upon the upper runs of the ribbons and provided at its ends with gear wheels which mesh with the teeth of the gear wheels upon the cylinder.

2. In a machine of the character described, a casing, a printing cylinder journaled therein and provided at its ends with gear wheels, an ink fountain located below the cylinder and having partitions which divide the same into compartments adapted to retain different colored ink, rollers journaled in the fountain, ribbons trained around said rollers, means for moving the ribbons by stages and operated from the cylinder and an ink distributing roller resting upon the upper runs of the ribbons and provided at its ends with gear wheels which mesh with the teeth of the gear wheels upon the cylinder.

In testimony whereof I affix my signature.

HIESTER SEIDERS.
